UNITED STATES PATENT OFFICE.

WARD B. STORY, OF BROOKLYN, NEW YORK.

LEAF-STEMMING MACHINE.

Application filed July 24, 1919. Serial No. 312,972.

The invention relates to apparatus for "stemming" or removing the stem or midrib from tobacco leaves as a preliminary to the manufacture of smoking or chewing tobacco, 5 or snuff.

The objects of the invention are to provide an apparatus which will be simple in construction, effective in operation and economical of manufacture and maintenance which 10 will not become clogged, wherein the leaf will not be injured, wherein that portion of the leaf near the butt of the stem will be removed, and wherein the stem or rib will be removed from the lamina clean and with 15 great rapidity, and without adhering lamina portions.

These and further objects will more fully appear in the following specification and accompanying drawings considered together or 20 separately.

One embodiment of the invention is illustrated in the accompanying drawings in which like parts are designated by similar characters of reference, and in which 25

Fig. 1 is a top plan view of the machine.

Fig. 2 is a side elevation of a portion of the apparatus.

Fig. 3 is a transverse section partly in side elevation of the machine, the section being 30 on the line 3—3 of Fig. 1.

Fig. 4 is an enlarged top plan view of a portion of the device partly in section, the section being taken on the line 4—4 of Fig. 5.

Fig. 5 is a section on the line 5—5 of Fig. 4.

Fig. 6 is a greatly enlarged side elevation of a portion of the device.

Fig. 7 is a bottom plan view of the guard rail, and

Fig. 8 is a section on the line 8—8 of Fig. 6.

The apparatus comprises a standard 1 carried on a base (not shown) by means of which the device is carried upon a floor. The standard is provided near its upper end with radiating arms 2 preferably three in 45 number.

The outer ends of the arms 2 carry cone rollers 3 on which is supported an annulus 4. The annulus is centered and retained in position on the rollers 3 by means of vertically 50 journaled rollers 5, also carried on the arms 2. The annulus 4 carries arms 6 on which is mounted an annular table 7.

An internal gear wheel 8 is carried by the annulus 4 and is engaged by a spur gear 9 mounted on a vertical shaft 10 rotatable in a 55 casing 11 supported on one of the arms 2. A bevel gear 12 is secured to the spur gear 9 and meshes with a bevel pinion 13 carried by a horizontal shaft 14 also mounted on the casing 11. A pulley 15 on the shaft 14 is 60 adapted to be driven from a line shaft (not shown) to impart motion to the shaft and thence to the annular table 7 which is thus given a rotary movement in the anticlockwise direction about the standard 1. 65

Carried on arms 16 projecting inward from the annulus 4 is a ring 17 on which the inner periphery of the table 7 rests. Carried by the ring 17 is a circular series of spaced, axially projecting pins 18, and between the 70 pins and the ring 17 is an annular blade 19. The blade is seated in a rabbet in the ring 17. The pins 18 are preferably formed of half round wire and the flat sides of the pins rest against the blade 19 and are held in position by blocks 20. Each block engages two pins and is secured to the ring 17 by a screw. The pins project above the upper edge of the blade 19 and the upper extremities of the pins are bent outward as shown. 80

Carried on arms 21 projecting from the standard on a higher plane than the arms 2 is a guard 22. The guard is of a curvature corresponding to that of the minor periphery of the ring 17, and extends partly around the 85 ring as shown in Fig. 1, and is disposed directly above the pins 18 and separated from them a short distance. One end 23 of the guard 22 is arranged on a line which cuts the circle forming the opening in the table 7 and 90 is extended downward nearly to the surface of the table as shown in Figs. 1 and 2. Carried by the curved portion of the guard 22 is a series of spring fingers 24 each comprising a horizontal portion 25 on a lower level 95 than the guard and which normally rests against the flat sides of the pins 18 and upon the exposed upper edge of the blade 19. The free end of each portion 25 is bent outward to lie alongside of and parallel to its neighbor. The spring portion 25 is immediately below the bent out portions of the pins whereby the inclined parts of the pins act to 100 retard movement of the spring fingers away

from the edge of the blade, and retain the portion 25 in the horizontal position. The horizontal portions 25 of the springs form a continuous spring surface extending from 5 the point A to the point B.

The table 7, and annulus 4 carrying the pins 18 rotate as a whole, while the arms 2, arms 21 and guard 22 are stationary.

Mounted within the casing 11 and projecting through the top thereof is a vertical shaft 26 carrying a spur gear 26^a driven from a pinion 27 on the shaft 10 through the intermediary of an idler pinion 28 within the casing. The shaft 26 is carried in a 10 long bearing 29 forming a portion of the casing 11.

Keyed to the shaft 26 outside of the casing 11 is a circular turret 30 having a peripheral recess 31. A circular series of tubular plungers 32 is carried in the turret 30. The upper end of each plunger extends into the recess 31, and the lower extremity of each is provided with an antifriction roller 33. The rollers engage a cam 34 rigidly secured to the bearing 29 of the casing 11. 20

A spindle 34^a is carried in each plunger and projects through the upper end thereof. Secured to the upper extremity of each spindle is a segmental head 35, and a spring 36 coiled around the shank of each spindle acts as a cushion for the head 35. The heads form a false bottom for the recess and are movable relatively to the bottom of the recess when the turret is rotated relatively to 25 the cam 34 as shown in Fig. 5. The spindles may be adjusted by means of nuts 37.

Each head is provided with an arc-shaped groove 38 the bottom of which is inclined from the rear or minor edge thereof toward the outer edge of the head and when the heads are in position as shown in Fig. 4, a circular groove extending around the false bottom and near the periphery thereof will be formed.

45 The upper wall of the recess 31 is provided with a dovetailed, circular groove in which is inserted an elastic, compressible ring 39. The ring 39 projects below the upper wall of the recess and cooperates with the grooves in the heads 35 when the latter are raised, as shown at the right in Fig. 5.

A sleeve 40 is mounted on the upper part of the casing 11. The sleeve encloses the cam 34 and the elements cooperating therewith, and engages the lower portion of the turret 30 and forms a closed casing which may be filled with lubricant as may the lower part 41 of the casing 11. Each of the heads is provided with a depending flange 35^a which overhangs the upper end of the sleeve 40. The flanges form a skirt extending around the turret and prevent the entrance of dirt or grit beneath the heads.

65 A butter board 42 is supported on one of the arms 2 and on the guard 22 and ex-

tends part way around the inner periphery of the table 7 and is positioned a short distance inside of the same, and a shelf or rest 43 is carried by the butter board.

The extremity of the guard 22 nearest the 70 point A is provided with a plate 44 on each side thereof. The plates straddle the pins 18 and each plate has an inclined lower edge for a purpose to be hereinafter described, and the guard carries an adjustable cutting 75 blade 45.

A sorting table 46 is mounted over the annular table 7 at any desired point.

The operation is as follows:

The leaves properly prepared for the 80 stemming operation are deposited on the table 46 and the operator takes his stand at that end of the table which lies over the annular table 7. The leaves are arranged 85 on the sorting table with the butt ends of the stems toward the inner side of the said table.

Power is applied to the pulley 15 and the 90 table 7 and turret 30 are caused to rotate in the anticlockwise direction. The peripheral speed of the turret will be considerably less than that of the inner edge of the table.

The operator will place the leaves one at a 95 time on the rotating table 7 each with its stem resting between two of the pins 18 and the butt end of the stem in engagement with the butter board 42. That portion of the stem between the pins and the butter board will rest upon the shelf 43 and be prevented from sagging. The rotation of the table 7 will carry the leaves toward the turret 30 and as 100 the stems pass under the guard 22 they will engage the lower, inclined edges of the plates 44 and be depressed into engagement with the upper edge of the annular blade 19.

The continued movement of the table 7 105 will bring the stem under the horizontal portion 25 of the first spring finger 24 which will be raised by the stem. The upward movement of the finger is resisted by the inclined bend of the fingers, and the stem is held in the gap between two pins, the blade 19 and the finger 24. The stem will remain in the said gap until it is finally withdrawn.

As the table carries the leaf further in 110 its travel, that end of the stem projecting inward of the pins will be directed into the recess 31 of the turret 30. The rotation of the turret is so timed relatively to the table and to the cam 34 that as the heads 35 approach the table at the point A, where the periphery of the turret is in proximity to the inner periphery of the table and to the pins 18, the heads are at the lower-most point of their movement. The end of the stem is therefore inserted in the recess between a head and the upper wall of the recess.

When a head reaches the point A it will be moved upward by the cam and the butt of the stem will be clamped between the head 120

and the ring 39. The ring being of soft rubber or other compressible material, will be compressed by the stem but the portion of the ring at each side of the stem will contact with the inclined bottom of the groove 38 and be bent or crowded inward toward the axial line of the turret. This will tend to draw the stem inward and supplement the clamping effect of the head on the stem and prevent its withdrawal from the recess.

As the periphery of the rotating turret begins to travel away from the pins after passing the point A the stem will be drawn through the gap between the pins while the lamina will be prevented from passing because of the pins; and the pressure of the spring fingers 24 will force the stem against the blade 19 and the fingers and blade will also tend to prevent the passage of the lamina.

When the head engaging the butt of the stem reaches the point C diametrically opposite the point A the tip of the longest stem will be at the point B and the stem will be wholly withdrawn from the lamina, which will then be forced off the table 7 by the extension 23 of the guard 22.

When the head engaging the butt of the stem reaches the point C the cam groove 30 will depress the plunger 32 and head 35 and release the stem, which will fall out of the recess of the turret.

If it is desirable that a portion of the stem near the end thereof be retained in the lamina the knife 45 is placed in position on the guard 22 and as the stem is borne under the knife it is severed and the thin end remains in the tip of the lamina. The knife may be adjusted to cut off as much or as little of the stem as desired as it is adjusted toward or away from the point A.

By changing the proportions of the gear chain 26, 27 and 28 the speed of rotation of the turret relatively to that of the table may be varied and the machine adjusted to operate on long or short leaves.

The gap through which the stem is drawn is always rectangular being bounded by two of the pins 18, the edge of the blade 19 and a spring finger 24-25, and these four elements will always be in position to prevent any part of the lamina from being drawn through the gap.

As the stem is drawn through the gap its diameter grows gradually less, but the elasticity of the spring fingers supplemented by the resistance to upward movement by the outturned ends of the pins 18 will hold the fingers in contact with the stems until the latter are wholly withdrawn from the lamina or are severed by the knife 45.

The outer faces of the pins 18 being flat, and the edge of the blade being either flat or sharpened, as desired, will present more or less sharp edges to the stem and the

lamina will be scraped from the stem instead of the stem being torn from the lamina as in the present forms of stemming machines.

The wire of the fingers 24-25 may be, 70 and preferably is, of angular cross section so that there will be formed sharp edges to scrape the lamina away from the stem, and the latter will be removed from the leaf cleaned entirely from any part of the lamina. 75

The spring cushions 36 of the heads 35 and the yielding ring 39 will prevent the stem from being cut or broken off by the withdrawing mechanism.

The fact that the end of one spring finger 80 overlaps the next finger insures the stem being always under a finger and held in engagement with the edge of the blade 19.

The periphery of the turret 30 at the point A where the butt of the stem is taken is in 85 close proximity to the pins 18 and when the stem is received in the recess 31 the lamina always will be on the opposite side of the pins and when the stripping begins as the peripheries of the turret and table 7 move 90 away from each other, none of the laminae will adhere to that portion of the stem between the pins and the head grasping the butt of the stem.

The speeds of the table 7 and turret 30 95 are constant during the operation, but because of the difference in diameter of those elements the speed with which the stem is withdrawn from the lamina will increase 100 gradually as the inner periphery of the table recedes from the periphery of the turret. This movement of the table relatively to the turret will cause the stem to be drawn diagonally through the gap between the pins whereby the angular edges of the pins will 105 have a more effective scraping action on the stems.

As the pins recede from the turret by the rotation of the table and the angularity of the gap relatively to the point on the turret 110 at which the stem is grasped increases, and the stem is drawn diagonally through the gap, the effective width of the gap decreases. This decrease in the gap width will correspond more or less with the gradually reducing diameter of the stem as the point of the leaf is approached, and the spring fingers pressing down on the stems at all times will insure the scraping of the stem on four sides at all times irrespective of the size of 115 the stem.

In accordance with the provisions of the patent statutes I have described the principle of my invention, together with the apparatus which I now consider to represent the best embodiment thereof, but I desire to have it understood that the apparatus shown is merely illustrative, and that the invention may be carried out in other ways.

Having now described the invention, what 120

is claimed and desired to be secured by Letters Patent, is—

1. An apparatus for removing the stems from leaves, which comprises means for holding a leaf, means for moving the stem relatively to the lamina, members forming a gap through which the stem moves, said gap having four walls, one of said walls being movable relatively to all of the other walls of the gap.

2. An apparatus for removing the stems from leaves, which comprises means for holding a leaf, means for moving the stem relatively to the lamina, members forming a gap through which the stem moves, said gap having four walls, one of said walls being movable relatively to all of the other walls of the gap by engagement of the stem with the movable wall.

3. An apparatus for removing the stems from leaves, which comprises means for holding a leaf, means for moving the stem relatively to the lamina, members forming a gap through which the stem moves, said gap having rigid walls, and a wall formed of flexible material.

4. An apparatus for removing the stems from leaves, which comprises means for holding a leaf, means for removing the stem relatively to the lamina, members forming a rectangular gap through which the stem is moved, said gap having three rigid walls and one flexible wall.

5. An apparatus for removing the stems from leaves, which comprises means for holding a leaf, means for removing the stem relatively to the lamina, members forming a gap through which the stem is moved, the walls of said gap preventing movement of the lamina through the gap, said gap having three rigid walls and one flexible movable wall, and means for retarding the movement of the flexible wall.

6. An apparatus for removing the stems from leaves, which comprises means for holding a leaf, means for removing the stem relatively to the lamina, members forming a gap through which the stem is moved, the walls of said gap preventing movement of the lamina through the gap, said gap having three rigid walls and one flexible movable wall, and pins engaging the flexible wall for retarding the movement of the wall.

7. An apparatus for removing the stems from leaves, which comprises a rotating table for carrying the leaves with their ends projecting beyond one edge thereof, means carried by the table for holding the lamina of the leaves thereon, a rotating member associated with the table and carrying means adapted to grasp the projecting stems upon rotation, and means for rotating the table and member at different speeds to cause the grasping and withdrawal of the stems from the laminae.

8. An apparatus for removing the stems from leaves, which comprises a rotating table for carrying the leaves, a rotating element, said table and element moving in the same direction, means carried by the element for grasping the stems whereby the relative rotation of the element and table will withdraw the stems from the table, and means for preventing the withdrawal of the lamina from the table.

9. An apparatus for removing the stems from leaves, which comprises a rotating table for carrying the leaves, a rotating element, said table and element moving in the same direction, means carried by the element for grasping the stems whereby the relative rotation of the element and table will withdraw the stems from the table, and means carried by the table for preventing the withdrawal of the lamina from the table.

10. An apparatus for removing the stems from leaves, which comprises a rotating table for carrying the leaves, said table being provided with spaced members forming a series of gaps for receiving the projecting portions of the stems, a rotating device cooperating with the table and drawing the stems through the gaps, the walls of the gaps preventing the drawing of the lamina through the gaps.

11. An apparatus for removing the stems from leaves, which comprises a rotating table for carrying the leaves, said table being provided with spaced members forming a series of gaps for receiving the projecting portions of the stems, a rotating device cooperating with the table and drawing the stems through the gaps, the walls of the gaps preventing the drawing of the lamina through the gaps, and means for resisting the withdrawal of the stems.

12. An apparatus for removing the stems from leaves, which comprises a rotating table for carrying the leaves, said table being provided with spaced members forming a series of gaps for receiving the projecting portions of the stems, a rotating device cooperating with the table and drawing the stems through the gaps, the walls of the gaps preventing the drawing of the lamina through the gaps, and elastic means for resisting the withdrawal of the stems.

13. An apparatus for removing the stems from leaves, which comprises a rotating table for carrying the leaves, said table being provided with spaced members forming a series of gaps for receiving the projecting portions of the stems, a rotating device cooperating with the table and drawing the stems through the gaps, the walls of the gaps preventing the drawing of the lamina through the gaps, and spring fingers for resisting the withdrawal of the stems.

14. An apparatus for removing the stems from leaves, which comprises a rotating ta-

ble for carrying the leaves, said table being provided with spaced members forming a series of gaps for receiving the projecting portions of the stems, a rotating device co-operating with the table and drawing the stems through the gaps, the walls of the gaps preventing the drawing of the lamina through the gaps, there being four walls defining said gaps, the walls engaging the stems and scraping the lamina therefrom.

15. An apparatus for removing the stems from leaves, which comprises a rotating table for carrying the leaves, said table being provided with spaced members forming a series of gaps for receiving the projecting portions of the stems, a rotating device co-operating with the table and drawing the stems through the gaps, the walls of the gaps preventing the drawing of the lamina through the gaps, there being four walls defining said gaps, the edges of the walls being angular, the edges engaging the stem and scraping the lamina therefrom.

16. An apparatus for removing the stems from leaves, which comprises a table for receiving the leaves, said table having a central circular opening therein with the butts of the stems projecting into the opening, a circular turret within the confines of the table, the diameter of the turret being less than that of the diameter of the opening in the table, the turret being mounted eccentric to the table with its periphery in close proximity to a point on the periphery defining the opening of the table, means carried by the turret for grasping the projecting butts, means for rotating the table and turret in the same direction whereby the butts will be withdrawn from the table, and means for preventing withdrawal of the lamina from the table.

17. An apparatus for removing the stems from leaves, which comprises a table for receiving the leaves, said table having a central circular opening therein with the butts of the stems projecting into the opening, a circular turret within the confines of the table, the diameter of the turret being less than that of the diameter of the opening in the table, the turret being mounted eccentric to the table with its periphery in close proximity to a point on the periphery defining the opening, means carried by and movable relatively to the turret for grasping the projecting butts, means for rotating the table and turret in the same direction whereby the butts will be withdrawn from the table, and means for preventing withdrawal of the lamina from the table.

18. An apparatus for removing the stems from leaves, which comprises a table for receiving the leaves, said table having a central circular opening therein with the butts of the stems projecting into the opening, a circular turret within the confines of the table,

the diameter of the turret being less than that of the diameter of the opening in the table, the turret being mounted eccentric to the table with its periphery in close proximity to a point on the periphery defining the opening, means movable relatively to the turret for grasping the projecting butts, means for rotating the table and turret in the same direction whereby the butts will be withdrawn from the table, and means for preventing withdrawal of the lamina from the table.

19. An apparatus for removing the stems from leaves, which comprises a table for receiving the leaves, said table having a central circular opening therein with the butts of the stems projecting into the opening, a circular turret within the confines of the table, the diameter of the turret being less than that of the diameter of the opening in the table, the turret being mounted eccentric to the table with its periphery in close proximity to a point on the periphery defining the opening, means movable relatively to the turret for grasping the projecting butts, means for moving the movable means, means for rotating the table and turret in the same direction whereby the butts will be withdrawn from the table, and means for preventing withdrawal of the lamina from the table.

20. An apparatus for removing the stems from leaves, which comprises a table for receiving the leaves, said table having a central circular opening therein with the butts of the stems projecting into the opening, a circular turret within the confines of the table, the diameter of the turret being less than that of the diameter of the opening in the table, the turret being mounted eccentric to the table with its periphery in close proximity to a point on the periphery defining the opening, means movable relatively to the turret for grasping the projecting butts, a cam for moving the movable means, means for rotating the table and turret in the same direction whereby the butts will be withdrawn from the table, and means for preventing withdrawal of the lamina from the table.

21. An apparatus for removing the stems from leaves, which comprises a table for receiving the leaves, said table having a central circular opening therein with their butts extending into the opening, a series of spaced, axially projecting pins carried by the table with the stems resting in the spaces between the pins, a circular turret within the opening, said turret being mounted eccentric to the table, the periphery of the turret being at one point in close proximity to the periphery defining the opening, there being a peripheral groove or recess in the turret, said recess being in approximately the plane of the table, whereby the project-

ing stems will enter the recess, a wall of said recess being movable, means for moving the wall to grasp the projecting stems of the leaves, means for rotating the table and turret in the same direction, whereby the turret will withdraw the stems from the table, the pins acting to prevent the withdrawal of the lamina whereby the stems will be separated from the lamina.

10 22. An apparatus for removing the stems from leaves, which comprises a table for receiving the leaves, said table having a central circular opening therein with their butts extending into the opening, a series of
15 spaced, axially projecting pins carried by the table with the stems resting in the spaces between the pins, a circular turret within the opening, said turret being mounted eccentric to the table, the periphery of the turret being at one point in close proximity to the periphery defining the opening, there being a peripheral groove or recess in the turret, the bottom of said recess being normally in approximately the plane of the
20 top of the table, whereby the projecting stems will enter the recess, a wall of said recess comprising a series of segmental movable heads, means for moving the segments to grasp the projecting stems of the leaves,
25 means for rotating the table and turret in the same direction whereby the turret will withdraw the stems from the table, the pins acting to prevent the withdrawal of the lamina whereby the stems will be separated
30 from the lamina.

23. An apparatus for removing the stems from leaves, which comprises a table for receiving the leaves, said table having a central circular opening therein with their butts 40 extending into the opening, a series of spaced, axially projecting pins carried by the table with the stems resting in the spaces between the pins, a circular turret within the opening, said turret being mounted eccentric to the table, the periphery of the turret being 45 at one point in close proximity to the periphery defining the opening, there being a peripheral groove or recess in the turret, the bottom of said recess being normally in approximately the plane of the top of the table, whereby the projecting stems will enter the recess, a wall of said recess comprising a series of segmental movable heads, a cam for 50 moving the segments to grasp the projecting stems of the leaves, means for rotating the table and turret in the same direction whereby the turret will withdraw the stems from the table, the pins acting to prevent the withdrawal of the lamina whereby the stems 55 will be separated from the lamina.

24. An apparatus for removing the stems from leaves, which comprises a table for receiving the leaves, said table having a central circular opening therein with their butts

extending into the opening, a series of spaced, axially projecting pins carried by the table with the stems resting in the spaces between the pins, a circular turret within the opening, said turret being mounted eccentric to the table, the periphery of the turret being at one point in close proximity to the periphery defining the opening, there being a peripheral groove or recess in the turret, the bottom of said recess being in approximately the plane of the top of the table, whereby the projecting stems will enter the recess, a wall of said recess comprising a series of segmental movable heads, a cam for moving the segments to grasp the projecting stems of the leaves, means for rotating the table and turret in the same direction whereby the turret will withdraw the stems from the table, the pins acting to prevent the withdrawal of the lamina whereby the stems will be separated from the lamina, said cam acting to release the stem after the laminae have been separated therefrom.

25. An apparatus for removing the stems from leaves, which comprises a table for receiving the leaves, said table having a central circular opening therein with their butts extending into the opening, a series of spaced, axially projecting pins carried by the table with the stems resting in the spaces between the pins, a circular turret within the opening, said turret being mounted eccentric to the table, the periphery of the turret being at one point in close proximity to the periphery defining the opening, there being a peripheral groove or recess in the turret, said recess being in approximately horizontal alignment with the pins, whereby the projecting stems will enter the recess, a wall of said recess comprising a series of segmental, spring cushioned, movable heads, a cam for moving the segments to grasp the projecting stems of the leaves, means for rotating the table and turret in the same direction whereby the turret will withdraw the stems from the table, the pins acting to prevent the withdrawal of the lamina whereby the stems will be separated from the lamina, said cam acting to release the stem after the leaves have been separated therefrom.

26. An apparatus for removing the stems from leaves, which comprises a table for receiving the leaves, said table having a central circular opening therein with their butts extending into the opening, a gauge against which the stems abut to limit the extension of the butts into the space, a series of spaced, axially projecting pins carried by the table with the stems resting in the spaces between the pins, a circular turret within the opening, said turret being mounted eccentric to the table, the periphery of the turret being in close proximity to the edge of the table which defines the opening, there being a pen- 115
120
125

5 peripheral groove or recess in the turret, said recess being in approximately horizontal alignment with the pins, whereby the projecting stems will enter the recess, a wall of
 10 said recess being movable, means for moving the wall to grasp the projecting stems of the leaves, means for rotating the table and turret in the same direction whereby the turret will withdraw the stems from the
 15 table, the pins acting to prevent the withdrawal of the lamina whereby the stems will be separated from the lamina.

27. An apparatus for removing the stems from leaves, which comprises a table for receiving the leaves, said table having a central circular opening therein with their butts extending into the central opening in the table, a series of spaced, axially projecting pins carried by the table with the stems resting in the spaces between the pins, a circular turret within the opening, said turret being mounted eccentric to the table, the periphery of the turret being in close proximity to the inner edge of the table at one point on the table, there being a peripheral groove or recess in the turret, said recess being in approximately horizontal alignment with the pins, stationary means for supporting the projecting butts and directing the same to the recess, whereby the projecting stems will enter the recess, a wall of said recess being movable, means for moving the wall to grasp the projecting stems of the leaves, means for rotating the table and turret in the same direction whereby the turret will withdraw the stems from the table, the pins acting to prevent the withdrawal of the lamina whereby the stems will be separated from the lamina.

28. An apparatus for stemming leaves, which comprises a base, a table for receiving the leaves, said table having a central circular opening therein, a circular series of spaced, axially projecting pins carried by the table near the edge of the central opening therein, the stems of the leaves lying within the spaces between the pins and projecting into the central opening in the table, a member concentric with the pins for limiting the projection of the stems into the space, a shelf carried by the member for supporting the projecting stem, an annular element carried by the base and engaging the pins and upon which the stems rest, an elastic device for engaging the stems with the element, a turret within the opening defined by the table, there being a peripheral recess in the turret, the periphery of the turret being in close proximity to the inner periphery of the table, means for rotating the table and turret in the same direction, said shelf directing the projecting stems into the recess, means carried by the turret for grasping the stems whereby the continued rotation of the turret and table will cause the stems to be withdrawn from the table, the element, pins and elastic device preventing withdrawal of the lamina whereby the stems will be removed from the lamina, means operated by the movement of the turret for releasing the withdrawn stems and means for removing the stemmed lamina from the table.

will cause the stems to be withdrawn from the table, the element, pins and elastic device preventing withdrawal of the lamina whereby the stems will be removed from the lamina, means operated by the movement of the turret for releasing the withdrawn stems and means for removing the stemmed lamina from the table.

29. An apparatus for stemming leaves, which comprises a base, a table for receiving the leaves, said table having a central circular opening therein, a circular series of spaced, axially projecting pins carried by the table near the edge of the central opening therein, the stems of the leaves lying within the spaces between the pins, a member concentric with the pins for limiting the projection of the stems, a shelf carried by the member for supporting the projecting stems, an annular element carried by the base and engaging the pins and upon which the stems rest, an elastic device for engaging the stems with the element, said elastic element comprising independent sections, a portion of one section overlapping the next adjacent section, the pins having inclined portions for resisting movement of the elastic element, a turret within the opening defined by the table, there being a peripheral recess in the turret, the periphery of the turret being in close proximity to the inner periphery of the table, means for rotating the table and turret in the same direction, said shelf directing the projecting stems into the recess, means carried by the turret for grasping the stems whereby the continued rotation of the turret and table will cause the stems to be withdrawn from the table, the element, pins and elastic device preventing withdrawal of the lamina whereby the stems will be removed from the lamina, means operated by the movement of the turret for releasing the withdrawn stems and means for removing the stemmed lamina from the table.

30. An apparatus for stemming leaves, which comprises a table for supporting the leaves, said table having a central circular opening therein with their stems projecting into the opening, there being members forming gaps on the table in which the stems lie, a circular turret located in the space and eccentric with the table, said turret having means for grasping the projecting stems, means for rotating the table and turret at a constant speed whereby the stems will be withdrawn from the table through the gaps, and means whereby the gaps will be reduced in width and depth as the stems are withdrawn.

31. An apparatus for stemming leaves which comprises a table having a central circular opening for supporting the leaves with their stems projecting into the opening, members associated with the table and defin-

ing gaps adapted to receive the stems, a circular turret located within the circular opening and eccentric with the table, said turret having means for grasping the projecting stems, means for rotating the table and turret at a constant speed whereby the stems will be withdrawn from the table diag-

onally through the gaps, and means whereby the effective widths of the gaps will be reduced as the stems are withdrawn. 10
